UNITED STATES PATENT OFFICE.

JAMES S. PHILPOTT, OF WINDSOR, CALIFORNIA.

WINDMILL.

SPECIFICATION forming part of Letters Patent No. 389,007, dated September 4, 1888.

Application filed September 14, 1887. Serial No. 249,724. (No model.)

To all whom it may concern:

Be it known that I, JAMES S. PHILPOTT, of 5
Windsor, county of Sonoma, and State of California, have invented an Improvement in
Windmills; and I hereby declare the following
to be a full, clear, and exact description
thereof.

My invention relates to the class of windmills; and my invention consists in the novel 10
details of construction and arrangement hereinafter fully described and claimed.

Referring to the accompanying drawing, the figure is a perspective view of my windmill.

15 A is the windmill-tower, having a standard, a, to which is secured the journal sockets or bearings a', in which the stem b of the turn-table B is mounted and pivoted. The turn-table B is a single casting made, as shown, 20 with a hollow stem, b, a body portion, and a top portion, b', at right angles and in boxes, on which the shaft C of the wind-wheel D is journaled. The wheel D consists of a hub plate or flange, d, to which are bolted at d' 25 the blade-arms d'', which are preferably triangular in cross-section and extend outwardly along the blades d''' to the connecting-braces d'' near the outer ends of said blades, and said arms are bolted to the braces and through the 30 blades. They are also bolted to the blades at a point nearer the hub-flange, as shown at d''.

On the inner end of the wheel-shaft C is a 35 crank-disk, E, which is provided with a diametrically-located dovetailed groove, in which is fitted and adapted to slide a dovetailed bar, e, which is provided with a wrist-pin, e', to which is fitted the boxing f of the pitman 40 F of the pump. It will be seen that by the movement of the bar e the throw of the crank 45 may be varied as desired.

G is the vane, which has a stem or shank, g, the inner end of which is pivoted by a bolt, g', to the head h of a pintle or hinged pin, H, which is fitted in socket-bearings b'' upon the 50 top of the stem b of the turn-table B. The vane can move on its bolt g' as a center through an arc in a vertical plane, and can move with the pintle H as a center through an arc in a horizontal plane, and the connection at g' is such as to steady and keep the vane G from turning sidewise, being adapted

to hold it straight in whatever position it may assume.

In order to keep the pin H from having a tendency to rise from its socket-bearings b'' 55 when the vane moves upwardly, I have formed on the head h an inwardly and downwardly curved hook h', which passes over the rim of the upper bearing b'' and engages it underneath. In said rim, however, at a point near 60 where it joins the main body of the stem b, is made a groove, b'', in which the hook h' is adapted to fit when the vane is being adjusted in the first instance, so that the end of said hook may reach its proper position under the rim 65 of the bearing and remain so when the vane is in operation, it then traveling under the rim and not in proximity to the groove b''.

Extending outwardly from the top of the turn-table B is an arm, I, the end of which is 70 outside of the vertical plane of the pintle H, which is the pivotal center of the vane, and to this arm is connected a hook, J, through the other end of which passes the end of the link K, said end receiving nuts k on each side 75 of the hook J, so that by setting up the nuts the link K may be tightened to return the vane to position in case it sags. The other end of the link K is attached by a loose hinged joint at k' to the vane G at its center. The 80 effect of this construction, it will be seen, is that when the vane is forced around by the wind in order to throw the wheel into the wind it not only turns on its pivotal center at H, but by reason of its link-connection K 85 it rises at the same time on its pivotal bolt g', and returns from this position by its own gravity. In this movement, as before stated, it keeps perfectly straight, the connection at g' providing for the proper support and the 90 attachment of the link K to the middle of the vane effecting its operation without undue strain.

The vane G is also connected, as usual, with the turn-table by means of the chain L, which 95 is attached to the shank of the vane and to an outwardly-extending arm, M, secured to the turn-table.

In order to throw the mill out of the wind, I have the following mechanism: Attached to 100 the shank g of the vane is a cord, N, which passes around a guide-pulley, n, in the arm

M, and thence to a guide-pulley, n' , on the turn-table, and thence downwardly through the central stem of said turn-table.

The general operation of the mill is similar to that of mills of this class, the invention herein lying in the improved construction and arrangement of the parts.

Having thus described my invention, what I claim as new, and desire to secure by Letters to Patent, is—

An improved windmill comprising the combination of a turn-table and a vane for regulating the mill, the vertical pindle H, having a head, h, with downturned hook h', and the bearing on the turn-table having a rim with

which the hook h' engages to prevent the pindle from rising, said bearing having also a groove, b³, to initiate the engagement, the bolt g', pivoting the vane-shank to the pindle, the arm I, projecting from the turn-table and having its outer end out of line with the pindle, the link K, hook J, with its adjusting-nuts, and the operating-cords, all constructed and arranged to operate substantially as herein described.

In witness whereof I have hereunto set my hand.

JAMES S. PHILPOTT.
